SILENCING PAD

Harry C. Yaeger, West Hartford, Conn., assignor
to Underwood Corporation, New York, N. Y., a
corporation of Delaware

Application December 17, 1948, Serial No. 65,839

1 Claim. (Cl. 248—22)

1

The present invention relates to silencing pads for typewriting and business machines.

It is an object of the present invention to provide a silencing pad having means whereby a typewriting or business machine may be readily detachably secured thereto without the use of screws or other separate fastening means.

It is another object of the present invention to provide a silencing pad which is usable with any make or style of typewriter and which may be economically manufactured and easily assembled.

It is a further object of the present invention to provide a silencing pad usable with any make or style of typewriter and which is also usable with any style of desk.

It is a still further object of the present invention to provide a silencing pad comprised of a plurality of parts so constructed and arranged that the major parts are adapted for use with any make or style of typewriter or with any style of desk.

These and further objects, features and advantages will become more readily apparent as the specification proceeds.

Referring now to the drawings:

Fig. 1 is a plan view of a silencing pad made in accordance with the present invention showing same provided with fittings adapting it for use with an "Underwood" electric typewriter.

Fig. 2 is an enlarged view taken along the line 2—2 of Fig. 1 and diagrammatically showing a typewriter in position upon the pad.

Fig. 3 is a plan view of a portion of the silencing pad made in accordance with the present invention.

Fig. 4 is an enlarged view taken along the line 4—4 of Fig. 1.

Fig. 5 is a plan view, partially broken away, showing the silencing pad of the present invention provided with fittings somewhat different from the fittings shown in Fig. 1.

Fig. 6 is a plan view similar to Fig. 5 but showing a still different set of fittings.

Fig. 7 is a diagrammatic view showing a typewriter and silencing pad secured to a desk and showing the desk in its folded condition, and

Fig. 8 is an enlarged view taken along the line 8—8 of Fig. 5 and diagrammatically showing a typewriter in position upon the pad.

The silencing pad of the present invention is composed of four basic or major parts. As shown in the drawings, these parts are a cushion 10 of fibrous material, such as felt, a semi-rigid cover 11 for the cushion and a pair of relatively heavy plates 12.

The cover 11 is coextensive with the cushion and is provided with a marginal flange 13 extending downwardly over the edges of the cushion. The cover 11 may be made of any suitable material, such, for example, as sheet steel, and it serves the twofold purpose of protecting the

2

cushion from dirt and of distributing the weight of the typewriting or other machine more evenly over the surface of the cushion so that same will not become packed down under the feet of the machine. If desired, the cover may be secured to the cushion by means of glue, or other suitable securing means.

As best seen in Fig. 3, the cover is provided with a plurality of symmetrically arranged openings, or slots, 14. The cushion 10 is provided with a plurality of openings 15 aligned with the slots 14, for a purpose to presently appear.

The plates 12 are identical and each is provided with a plurality of tabs 16. The plates 12, in the embodiment shown, are made of relatively heavy stock so that they are substantially rigid, though it is to be understood that in some instances these plates may be somewhat flexible without departing from the spirit of the present invention. At any rate, the plates 12 together with the cover 11 provide double laminations between the machine and the cushion, as will later more fully appear.

For adapting the silencing pad of the present invention for use with various makes and styles of machines and various styles of desks, the plates 12 are to be provided with different fittings, as will presently more fully appear.

The plates 12 may conveniently be attached to the cover 11 by extending the tabs 16 through the appropriate openings 14 and bending them over, as shown in Fig. 4. The openings 15 in the cushion readily permit this bending operation in cases where the cushion has been previously secured to the cover 11.

A pair of holes 17, extending through each of the plates 12, the cover 11 and the cushion 10, may be provided for accommodating bolts or other means for securing the pad to a desk.

In Figs. 1 and 2 are shown fittings which are appropriate when the pad is to be used with an "Underwood" electric typewriter, and the desk is of the type which causes the typewriter to slope rearwardly when the desk is folded to conceal the machine. Each of the plates 12 is provided with a cup-like element 18 for receiving positioning means carried by the machine, as will readily be understood. Each plate 12 is also provided with a fastening means, generally indicated at 19, for detachably securing the typewriter to the pad.

As may best be seen in Fig. 2, the fastening means 19 comprises a plate 20 bent upwardly at its forward end to provide an extension 21. The plate 20 is provided with an opening in the form of a slot 22 within which is loosely fitted a member 23. The member 23 is provided at one end with a hooked portion 24 and at its other end has an operating tab 25. A leaf spring 26, riveted or otherwise secured to the plate 20 at 27, extends through an opening 28 in the member 23 and bears against the upper side of the operating tab 25 to resiliently hold the member 23 in the position shown in Fig. 2.

The typewriter, the base of which is partially indicated at 29, has attached thereto, by means of a screw 30, a fitting 31 provided with a slot 32. Near its front, the typewriter is provided with positioning means in the form of a rubber disc 33 secured to the under side of the machine by a screw 34. It will be understood that there is a fitting 31 and a disc 33 on each side of the machine.

When the machine is to be used with the silencing pad, the discs 33 are placed within the cups 18, and as the machine is lowered into resting position, the ends of the fittings 31 press against the rounded upper side of the hooked portions 24 and cam members 23 rearwardly against the action of the leaf springs 26 to the position shown in dotted lines in Fig. 2. As the machine reaches its lowest position, the springs 26 snap the members 23 back to the full-line position shown in Fig. 2 with the hooked portions 24 extending through the slots 32. The machine is then resting upon a pair of resilient runners 29, one runner extending lengthwise of the machine underneath either side thereof. When that part of the desk carrying the machine is level, it will be noted from Fig. 2 that there is no contact between the member 23 and the fitting 31; thus no vibrations will be transmitted through this connection. When the machine is sloped to the rear, as when the desk is folded, the hooked portion 24 will secure the typewriter against displacement, as will readily be understood.

With the fastening means 19 constructed as shown, it is apparent that the tab 25 must be raised to release the machine. This feature is advantageous over the older constructions wherein a tab is moved downward to release the machine inasmuch as there is less likelihood of the present fastener being accidentally released.

In Figs. 5 and 8 are shown fittings for the plates 12 which are adapted for use with an "Underwood" electric typewriter when the desk is of the type which when folded to conceal the machine causes the machine to slope toward the front. In this instance, the plates 12 are again provided with the cup-like element 18, but instead of the fastening means 19, each plate is provided with a member 35. The members 35 are bent at 36 so that their rear ends are spaced from the plates 12. The typewriter is provided underneath, near its rearmost edge, with a bar 37, secured thereto by means of screws 38 or otherwise. When the typewriter is to be used with a pad fitted as shown in Figs. 5 and 8, the bar 37 is first slipped beneath the members 35, and the discs 33 are then placed within the cup-like elements 18. Thus the elements 18 and the members 35 serve as means to locate the machine in a definite position and to releasably hold it in said position. When the desk is folded so that the typewriter slopes toward the front, the members 35, by cooperation with the bar 37, will prevent the machine from moving with respect to the pad. It will be observed from Fig. 8, however, that when the machine is level, there is no contact between the bar 37 and the members 35 and hence no vibrations will be transmitted through this connection.

Figs. 6 and 7 show fittings appropriate for use with an "Underwood" standard typewriter. The fittings are arranged in these two figures in such manner as to adapt the pad for use with the type of desk which causes the typewriter to slope toward the rear when the desk is folded, such folded condition being illustrated in Fig. 7. In

20 25 30 35 40 45 50 55 60 65 70 75 76

4 this instance, each plate 12 is provided near one end with a cup-like element 39. The cups 39 are somewhat larger than the cups 18 to accommodate the somewhat larger feet of the machine.

5 Near the end opposite the cup-like element 39, each plate 12 is provided with a fitting, generally designated 40, comprising a plate 41 having a pair of upwardly and inwardly extending flanges 42 and an end wall 43. In positioning an "Underwood" standard typewriter 44 upon the pad, the front feet 45 thereof are first slipped into the fittings 40 so that a lower rim 46 of each foot is resting against the end wall 43 and beneath the inwardly extending top edges of the flanges 42, as best seen in Fig. 7. The rear feet 47 are then positioned within the cup-like elements 39. Thus the elements 39 and the fittings 40 serve as means for supporting and for releasably holding the machine.

20 While only a few examples of the various possible fittings for the plates 12 have been shown, it is to be understood that other fittings are to be employed when the silencing pad is to be used with other makes and styles of machines.

25 30 35 40 45 50 55 60 65 70 75 76

The basic parts of the pad, that is, the cushion 10, the cover 11 and the plates 12, are universally usable with any style of machine. All that is necessary to adapt the pad of the present invention to a particular style of typewriter or business machine or to a particular style of desk is to provide the plates 12 with appropriate fittings. These fittings may be secured to the plates by spot welding, by riveting or by any other convenient means.

35 40 45 50 55 60 65 70 75 76

Thus it will be apparent that the major parts of the present pad may be economically manufactured in large numbers, and the fittings adapting it for use with different machines may be provided as they are needed. Likewise the appropriate fittings, or plates 12 carrying appropriate fittings, may be assembled in the field with the other parts of the pad, thus appreciably decreasing the bulk of stock necessary to be kept on hand at various sales outlets.

Having thus described the invention, what is claimed is:

A silencing pad for typewriting and business machines comprising a cushion of fibrous material having a coextensive semi-rigid cover connected thereto, a plurality of aligned openings through said cushion and said cover, the openings in said cushion being larger than the openings in the cover, a pair of relatively rigid monoplanar plates each having a plurality of tabs and carrying means constructed and arranged to support a typewriter or business machine and to detachably secure said machine to said plates, the tabs extending through the openings in said cover and being bent over to secure said plates to said cover.
